DESIGN FOR A REFRIGERATOR CABINET

Ernest Keller, Trenton, N. J.

Application March 26, 1945, Serial No. 118,695

Term of patent 3½ years

(Cl. D67—3)

To all whom it may concern:

Be it known that I, Ernest Keller, a citizen of no country and residing in the city of Trenton, in the county of Mercer and State of New Jersey, have invented a new, original, and ornamental Design for Refrigerator Cabinets, of which the following is a specification, reference being had to the accompanying drawing, forming part thereof.

Figure 1 is a perspective view of a refrigerator cabinet, showing my new design when the refrigerator door is in closed position.

Figure 2 is a similar view, showing my new design when the refrigerator door is in open position.

The other side of the refrigerator cabinet, not shown, is substantially plain.

I claim:

The ornamental design for a refrigerator cabinet, as shown and described.

ERNEST KELLER.
